US0D1083888S

(12) **United States Design Patent** (10) **Patent No.:** **US D1,083,888 S**
(45) **Date of Patent:** **** Jul. 15, 2025**

(54) **WIRELESS ELECTRONIC DEVICE**

- (71) Applicant: **PLUME DESIGN, INC.**, Palo Alto, CA (US)
- (72) Inventors: **Ming-Tsung Su**, Taipei (TW); **Nora Yan**, Taipei (TW); **Richard Chang**, Los Altos Hills, CA (US); **Jeffrey ChiFai Liew**, Millbrae, CA (US); **Miroslav Samardzija**, Mountain View, CA (US); **Liem Hieu Dinh Vo**, San Jose, CA (US)
- (73) Assignee: **PLUME DESIGN, INC.**, Palo Alto, CA (US)
- (**) Term: **15 Years**
- (21) Appl. No.: **29/942,122**

(22) Filed: **May 14, 2024**

(51) LOC (15) Cl. **14-03**

(52) U.S. Cl.

USPC **D14/240**

(58) **Field of Classification Search**

USPC D14/349-352, 358, 432, 433, 439, 137,

D14/140, 155, 230, 240, 242

CPC H01Q 1/2291; H01Q 1/246; H04W 88/08

CLAIM

The ornamental design for a wireless electronic device, as shown and described.

DESCRIPTION

FIG. 1 is a top perspective view of a wireless electronic device;

FIG. 2 is a bottom perspective view of the wireless electronic device;

FIG. 3 is a front side view of the wireless electronic device;

FIG. 4 is a rear view of the wireless electronic device;

FIG. 5 is a left side view of the wireless electronic device;

FIG. 6 is a right side view of the wireless electronic device;

FIG. 7 is a top view of the wireless electronic device; and,

FIG. 8 is a bottom view of the wireless electronic device.

The broken lines shown in the figures illustrate portions of the wireless electronic device that form no part of the claimed design.

1 Claim, 6 Drawing Sheets
